UNITED STATES PATENT OFFICE.

EDWARD R. SARGENT, OF NEW HAVEN, CONNECTICUT, ASSIGNOR TO
SARGENT & CO., OF SAME PLACE.

DESIGN FOR A COFFIN-SCREW.

SPECIFICATION forming part of Design No. 16,679, dated May 4, 1886.

Application filed March 18, 1886. Serial No. 195,753. Term of patent 14 years.

To all whom it may concern:

Be it known that I, EDWARD R. SARGENT, of New Haven, in the county of New Haven and State of Connecticut, have invented a new 5 Design for Coffin-Screws; and I do hereby declare the following, when taken in connection with accompanying drawings and the letters of reference marked thereon, to be a full, clear, and exact description of the same, and which 10 said drawings constitute part of this specification, and represent, in—

Figure 1, a side view; Fig. 2, a transverse section through the body.

This invention relates to a design for the 15 ornamental heads of screws such as used to secure the cover of coffins, and commonly called "coffin-screws;" and the design consists in the configuration and ornamentation of the head, as shown in the accompanying illustration, and hereinafter described.

A represents the body of the head, which is

of polygonal shape in transverse or horizontal section. The narrow faces forming the sides of the polygon run spirally around the body from the base B to the cap C, as indicated in 25 Fig. 1. These series of spiral-shaped faces forming the surface of the body constitute the essential feature of my invention, the shape of the base and cap not being material thereto.

I claim—

The design for a coffin-screw, consisting of a base and cap, with a body, A, between, the said body polygonal in shape in transverse section, the several faces running spirally around the body from the base to the cap, as 35 described, and shown in the accompanying illustrations.

EDWARD R. SARGENT.
